O. H. NANCE

OIL SEPARATOR

Filed Oct. 8, 1927

UNITED STATES PATENT OFFICE.

ORAN H. NANCE, OF BALTIMORE, MARYLAND.

OIL SEPARATOR.

Application filed October 8, 1927. Serial No. 224,984.

My invention relates to oil separators in general and particularly to a novel device for separating oil and other impurities from exhaust steam or condensate thereof in connection with locomotives equipped with a feed water heater of the closed type.

A further object of my invention resides in the provision of a simple, inexpensive and highly effectual apparatus which will operate automatically to remove oil and other impurities from the condensate of exhaust steam, thus permitting the return of the water in this condensate to the tank for reuse in the boiler, whereby the fuel, due to the transferring of heat in the tender tank, will be conserved.

The scope of my invention extends to whatever constructions may be defined by or included within the terms or language of the appended claims.

In the accompanying drawing:—

The figure illustrated represents a vertical sectional view of a preferred embodiment of my invention as applied to a locomotive tender tank.

My invention in the form or embodiment shown in the drawing and briefly described comprises a tender, 10, having a main water compartment, 11, which is separated from the coal compartment, 12, by means of the partition, 13. An opening, 14, may be conveniently located for the purpose of filling the tank, 11, with water, when desired.

At any convenient place within the water tank, 11, but preferably back of the coal compartment, 12, there is located a separate compartment, 15, hereinafter referred to as the condensate reservoir, which extends from the bottom of the water tank, 11, upwardly to and preferably through the top sheet, 16. This condensate reservoir is securely attached to the bottom of the main water compartment, 11, and water-tight joints are provided at that point as well as where it extends through top sheet, 16, such joints being obtained by any practicable method such as riveting or welding. A cover, 17, is fitted to the top of condensate reservoir, 15, in such manner as will prevent the escape of air or vapor around said cover.

A pipe, 18, extends throughout a greater portion of the length of the condensate reservoir, 15, and is provided at its upper end with a horizontal extension, 19, which is adapted to extend through an opening in the

side of the said condensate reservoir to permit the overflow of the liquid from the condensate reservoir into the main water compartment, 11, as clearly shown in the drawing. In order to maintain the level within the condensate reservoir substantially the same as the highest water level within the main water compartment, 11, I have found it desirable to have the outlet relatively close to the inside of the top sheet, 16.

For the purpose of permitting the free escape of air, vapor, or steam from the condensate reservoir to the atmosphere, I provide an opening near the upper extreme end of this reservoir in which is located a pipe, 20, of relatively small diameter. Since the escape of vapor or steam in cold weather may obstruct the vision of the train crew, I may plug up one end of the T, 21, which will, of course, force the vapor or steam downwardly through the pipe, 22. Although this pipe, 22, is shown as passing through the main water compartment, 11, and surrounded by a tube, 23, of a larger diameter, it is obvious, of course, that this pipe, 22, may be conducted on the outer side of the tender in any suitable manner.

Condensate is drained by gravity from the feed water heater on the locomotive through the pipe, 24, which is preferably located near the bottom of the main water compartment, 11. Suitable coils or return bends, 25, are adapted to be connected with the pipe, 24, so as to cool the condensate to the desired temperature, from which point a pipe, 26, extends upwardly and into the inner side of the condensate reservoir, 15, as indicated at 27, preferably at a point above the overflow pipe, 19. It is to be understood, of course, that water-tight joints must be provided at the points where the pipes leave and enter the various compartments.

For the purpose of emptying and cleaning the condensate reservoir, 15, without disturbing the water level within the main water compartment, 11, I provide a drain opening, 28, in the bottom thereof, which may be closed by a valve, 29. The overflow pipes, 18 and 19, are preferably formed of the same or a slightly larger diameter than the pipe, 27, so that the liquid within the condensate reservoir will readily flow out through the pipe, 19, at about the same rate of speed as the liquid flows into this reservoir through the pipe, 27, thereby maintaining substan-

tially the same level, within the condensate reservoir.

The temperature of the condensate is very high when it leaves the feed water heater 5 and as the result thereof, the oil is thoroughly mixed with the water forming what might be termed an emulsion. As the condensate travels through the pipe and coils, 10 24 and 25, its temperature is greatly reduced, however, and the heat is transferred to the water within the tank, 11, and the surrounding atmosphere. A greater portion of the condensate reservoir being surrounded by the greater body of water in the main compartment, 11, still further cools the condensate, 15 after it enters the condensate reservoir, 15, and thereby giving the lighter oils an ample opportunity to rise to the surface within the condensate reservoir while the 20 carbonized oil and other heavier impurities settle to the bottom.

Having, therefore, described the various details of my invention, it will be readily understood that this device will effectually 25 separate the oil and the heavier impurities from the water and, at the same time, permits the return of the water in this condensate to the tank for re-use in the boiler conserving the water supply, as well as saving 30 fuel by transferring heat from the condensate to the feed water supply in the tender tank.

I claim:—

1. In an oil separator, the combination of 35 a locomotive tender tank, having a main water compartment, a plurality of longitudinally extending coils located within the main water compartment for cooling the condensate, a pipe arranged to permit the liquid to 40 flow into the condensate reservoir, and an

overflow pipe arranged with respect to said reservoir as to permit the liquid from within the lower portion of said reservoir to pass upwardly through the overflow pipe and overflowing at a point substantially close to 45 the uppermost end of the main water compartment.

2. In an oil separator, the combination of 50 a locomotive tender, having a main water compartment, of a vertically mounted condensate reservoir separate from the water compartment and located within said compartment being closed at its lower end and extending substantially above the top of said main water compartment as to exclude the 55 commingling of water from said main water compartment, a pipe arranged to permit the liquid to flow into the condensate reservoir, and an overflow pipe arranged with respect to said reservoir as to permit the liquid from 60 within the lower portion of said reservoir to pass upwardly through the overflow pipe and overflowing at a point substantially close to the uppermost end of the main water compartment.

3. In an oil separator, the combination 65 with a locomotive tender tank having a main water compartment and separate therefrom, of a condensate reservoir arranged vertically 70 in said compartment, a condensate pipe having cooling coils and having communication with the upper end of the reservoir, an overflow pipe located within the condensate reservoir and arranged to maintain the liquid level therein to the substantial height of 75 said main water compartment, and means for permitting the escape of vapor from the upper end of the reservoir.

ORAN H. NANCE.
